UNITED STATES PATENT OFFICE.

FRANK WHITCOMB, WILLIAM LAVENDER, AND RAYMOND ARTHUR CALVERT, OF SMITHS FALLS, ONTARIO, CANADA, ASSIGNEES TO THE FROST & WOOD COMPANY, LIMITED, OF SMITHS FALLS, ONTARIO, CANADA, A CORPORATION.

CULTIVATOR.

Application filed November 28, 1921. Serial No. 518,418.

To all whom it may concern:

Be it known that we, FRANK WHITCOMB, WILLIAM LAVENDER, and RAYMOND ARTHUR CALVERT, all of the town of Smiths Falls, in 5 the Province of Ontario and Dominion of Canada, have invented certain new and useful Improvements in Cultivators, of which the following is a specification.

This invention relates to improvements in 10 cultivators, particularly to those of the type employing a plurality of mounted teeth carried on frames by which the teeth are raised or lowered from or to operative position, and the objects of the invention are to provide 15 simple and effective means operable during the movement of the machine by which the depth of cut or extent of lowering of the teeth of the cultivator may be regulated to correspond with the variations in the character 20 of the ground on which the cultivator is being used.

Further objects of the invention are to provide a device of this character which may be readily applied to existing types of cultivators without reorganization of the machine.

Further objects still are to generally improve and simplify the construction of the device to better adapt the various parts to 30 perform the functions required of it.

It consists essentially of the improved construction hereinafter described in detail in the accompanying specification and drawings.

35 In the drawings:

Figure 1 is a side elevation of an embodiment of the invention.

Figure 2 is a plan view of the same, only one set of teeth shown in full lines for the 40 sake of clarity in illustration.

Figure 3 is a detail in elevation of the operable parts of the adjusting mechanism.

Figure 4 is a cross-sectional detail on the line $\alpha-\alpha$, Figure 3.

45 Figure 5 is a sectional elevation of one of the supporting brackets.

Figure 6 is a detail in plan of the clutch for the power lift.

Figure 7 is a detail in elevation of the inferior parts of the clutch.

50 Figure 8 is a detail in elevation of one of the clutch members.

Figure 9 is a sectional elevation of an alternative form of the invention.

In the drawings, like characters of reference indicate corresponding parts in all the figures.

Referring to the drawings:

A indicates a truck having side wheels 10 and 11 and fore wheels 12 and 13 and a suitable hitching device 14. The truck carries a frame 15 from which the cultivator teeth 16 and 17 are supported by pivoted frames B, the pivoted frames being raised and lowered by suitable means to bring the teeth to 65 and from operative position. The well known means for this purpose which we have illustrated includes an operating shaft 18 mounted in suitable bearings 19 on the frame 15 having a crank 20 at one end connected by 70 a connecting rod 21 with a lever 22 connected to a cross rod 23 supported by brackets 24 on the frame 15. The rod 23 is formed square between the brackets 24 and has rigidly mounted thereon arms 25 which are slidably engaged by rods 26 extending to the frames B and being surrounded by springs 27 which extend from the arms 26 to the frames B, the said frames B being pivotally supported at their forward end on a cross 80 rod 28. We have shown only two of these frames in full lines in Figure 2, but it will be understood that in the completed machine a number of these frames would be usually provided side by side.

85 The shaft 18 is designed to be operated from the wheel 11 by means of a sprocket 29 carried by the wheel connected by a chain 30 with a sprocket 31 connected to a clutch member 32 (see Figures 6-8). The clutch member 32 is loosely mounted on the shaft 18 and is provided with internal teeth 33 designed to be engaged by a roller 34 carried on a lever 35 centrally fulcrumed within a recess 36 on a fixed clutch member 37. The 90 opposite end of the lever 35 to that carrying the roller 34 is connected by a link 38 with a corresponding lever 39 also mounted within the recess 36. The opposite end of the lever 39 to that connected to the link 38 is 95 secured to a spring 40 which extends between the end of the lever 39 and the clutch member 38 and is designed to tend to hold the roller 34 in engaged position.

The roller is designed to be moved to inoperative position by disengaging dogs 41 and 42 connected to the levers 35 and 39 projecting through slots 43 and 44 in the member 37 and designed to be engaged and operated by a roller 45 carried on a frame 46 on a control rod 47 and is journalled in brackets 48 and provided with an operating lever 49 from which an operating rod 50 extends, being slidably supported at its forward end in a bracket 51. The clutch member 37 is formed with diametrically opposite semicircular recesses 52 designed to receive the roller 45.

15 In operation, when the roller 45 is in the recess 52, the dog 41 or 42 is held in such position that the roller 34 is disengaged. When the roller 45 is by operation of the crank 46 removed from the slot 52, the 20 roller 34 under action of the spring 40 engages the teeth 33 causing the clutch member 37 to turn with the sprocket 31. This turns the shaft 18 to which the clutch member 37 is secured. When a half turn is 25 reached, however, the roller 45 will be engaged by the opposite dog 41 or 42 to that with which it was previously engaged and will operate the dog itself to engage the roller 34, the roller 45 at this point sliding 30 into one of the recesses 52. The half turn of the shaft 18 is effected through the mechanism previously described and through raising or lowering the frames B carrying the cultivator teeth.

35 It may be stated that the frames B are assisted in their return to normal position by means of a spring 72 extending from a lever 73 on the rod 23 to a suitable point on the frame 15. The shaft 47 is also maintained in normal position by means of a 40 spring 74 which extends from a link 75 connected to the lever 49 to a suitable point on the frame 15.

It may be stated that the mechanism so 45 far described is well known in the art and is, for instance similar to that shown on page 25 of the catalogue of the Frost & Woods Company, Limited, Smiths Falls, Ontario, 1920 edition. It will be seen in the 50 mechanism already described, no means are provided for adjusting the depth to which the cultivator teeth are lowered during movement of the machine. A certain amount of adjustment can be made by adjusting the tension of the spring 27 or the 55 angular position of the brackets 25, but these adjustments can not be made during operation of the machine. In order to provide for these adjustments, the connecting 60 rod 21 in place of being directly connected to the lever 22 is pivotally connected to a sliding cross head or connecting member 53 mounted on the lever 22 and connected to the rod 21 by means of a strap or casting

54 which is pivoted to the cross head by 65 a pivot pin 55 which also extends through a longitudinally extending slot 56 in the lever 22, the outer end of the strap or casting having screw threaded engagement with the rod 21.

70 The position of the cross rod 53 with respect to the lever 22 is designed to be adjusted by means of a screw 56^a which extends through the cross head and is journalled at its upper end in a bearing 57 connected to the lever 22. The upper end of the screw or spindle 56^a carries a bevel gear 58 which meshes with a corresponding bevel gear 59 on a stub shaft 60 which is journalled in a bracket 61 connected to the bearing 57. The stub shaft 60 is connected by a universal joint 62 with an operating rod or spindle 63, the forward end of which is squared and engaged with a sleeve 64 which has a correspondingly squared central perforation 65. The sleeve 64 is rotatably mounted in a bearing 66 on the bracket 51 and is provided at its forward end with a hand wheel 67 having a crank 68 thereon. It will be seen by these means rotary motion 90 may be given to the rod 63 at the same time longitudinal sliding movement of the same is provided for during raising and lowering of the cultivator teeth. It will further be seen that operation of the hand wheel 67 95 and consequent turning of the rod 63 will turn the screw 56^a adjusting the position of the cross head 53 on the lever 22 and thus varying the throw of the lever under action of the crank 20. This variation in throw of 100 the lever will produce a corresponding variation in the depth to which the cultivator teeth are lowered.

105 In the alternative form of the invention shown in Figure 9, the adjusting means are designed to be operated from a point adjacent to the driver's seat and placed at the front end of the machine, as in the preceding views. It may be stated that in the case of a cultivator which is designed to be 110 drawn by tractors, it is more convenient to adjust the mechanism from the forward part thereof, which is adjacent to the seat of the tractor for horse drawn cultivators, it is more desirable that the adjustment 115 should take place from the driver's seat on the cultivator. In Figure 9, C indicates the driver's seat, but in this instance the screw 56^a is turned by means of a crank 70 connected to the top thereof, the normal position of which is adjacent to the driver's seat. The remaining part of the mechanism is the same as that previously described.

120 It will be seen that the foregoing mechanism provides a simple and effective device 125 by which the amount of raising or lowering of the cultivator teeth may be adjusted during operation of the machine to correspond

with variations in the soil in different parts of a field in which the cultivator is being used.

As many changes could be made in the above construction and many widely different embodiments of our invention within the scope of the claims, constructed without departing from the spirit or scope thereof, it is intended that all matter contained in the accompanying specification and drawings shall be interpreted as illustrative and not in a limiting sense.

What we claim as our invention is:—

1. In a machine of the character described and in combination a pivoted frame, cultivating means carried thereby, a lever operatively connected to the frame and designed to raise and lower the same, an operating shaft and means connected to the operating shaft and designed to reciprocate the lever within given limits, means for adjusting the limits within which the lever is reciprocated, the said means comprising a cross head slidably mounted on the lever and a screw designed to adjust the position of the cross head.

2. In a cultivator of the character described and in combination a pivoted frame, cultivating means carried by the frame, a pivoted lever operably connected with the frame designed to raise and lower the same, an operating shaft, a crank on the operating shaft, a connecting rod connected to the crank and to the lever, means for adjusting the point of connection between the connecting rod and the lever, said means comprising a cross head slidably mounted on the lever, a bearing on the lever, a screw mounted in the bearing on the lever and operatively engaging the cross head.

3. In a cultivator of the character described and in combination a pivoted frame, cultivating means carried by the frame, a pivoted lever operatively connected to the frame designed to raise and lower the same, means for reciprocating the lever, screw means associated with the means for reciprocating the lever adapted to vary the throw thereof, and means operable from the forward part of the machine for turning the

screw.

4. In a cultivator of the character described and in combination a pivoted frame, cultivating means carried by the frame, a

pivoted lever operatively connected to the frame designed to raise and lower the same, means for reciprocating the lever, screw means associated with the means for reciprocating the lever adapted to vary the throw thereof, and means operable from the forward part of the machine for turning the screw, the said last mentioned means including a telescoping operating member designed to permit movement of the lever during raising and lowering of the frame.

5. In a cultivator of the character described and in combination a pivoted frame, cultivating means carried by the frame, a pivoted lever operatively connected to the frame designed to raise and lower the same, means for reciprocating the lever, screw means associated with the means for reciprocating the lever adapted to vary the throw thereof, and means operable from the forward part of the machine for turning the screw, said means including a gear connected to the screw, a rod operatively connected to the gear, a sleeve slidably engaging the rod designed to turn the same, and means for turning the sleeve.

6. In a cultivator of the character described and in combination a pivoted frame, cultivating means carried by the frame, a lever operatively connected to the frame and designed to effect raising and lowering the same, a cross head slidably mounted on the lever, a connecting rod pivotally connected to the cross head, means for reciprocating the end of the connecting rod, a bearing on the lever, a screw threaded therein and operatively connected to the cross head, a gear on the screw, a second gear meshed with the first mentioned gear, a stub shaft connected to the second gear, a bearing for the said stub shaft carried by the lever, an operating rod, a universal joint between the operating rod and the stub shaft, a sleeve slidably engaging the rod and designed to turn the same, and means for turning the sleeve.

In witness whereof we have hereunto set our hands in the presence of two witnesses.
